SKI POLE HANDLE

Howard Head, Cockeysville, Md. (% Head Ski Co., Inc., 15 W. Aylesbury Road, Timonium, Md.)

Filed Apr. 17, 1961, Ser. No. 64,766

Term of patent 14 years

(Cl. D34—14)

Fig. 1.

Fig. 2.

Fig. 3.

Fig. 5.

Fig. 4.

FIGURE 1 is the side elevational view of a ski pole handle showing my new design; and

FIGURE 2 is a front elevational view of the ski pole handle shown in FIGURE 1; and

FIGURE 3 is a rear elevational view of the ski pole handle shown in FIGURE 1; and

FIGURE 4 is a top view of the ski pole shown in FIGURE 1; and

FIGURE 5 is a bottom view of the ski pole handle shown in FIGURE 1.

I claim:

The ornamental design for a ski pole handle, as shown.
